ABSTRACT OF THE DISCLOSURE

A splicing device comprising pressing means, means for feeding a travelling web and the leading portion of a stand-by web between the pressing means, means for moving the pressing means towards each other to press a portion of the travelling web and the leading portion of the stand-by web together, and means for displacing the pressing means to travel jointly along the path of the webs whilst pressing the webs together. Advantageously, means are provided for pre-heating the pressing means so that webs of thermoplastic material or having splice portions with a thermoplastic coating are welded.

BACKGROUND TO THE INVENTION

The invention relates to splicing devices for connecting together webs of material, for example webs of cellulose glass, foil or paper. Such splicing devices are especially useful in connection with packing machines or cigarette making machine in which webs of material are alternately supplied from two reels, an end portion of a web supplied from one reel being connected to the beginning of a web supplied from the other reel so that the supply of web is not, or not unduly, interrupted.

It is an object of the invention to provide a splicing device by means of which two web portions are connected together without interrupting the supply of web material, and while travelling.

SUMMARY OF THE INVENTION

The invention consists in a splicing device comprising pressing means, means for feeding portions of a travelling web and a stand-by web between the pressing means, means for moving the pressing means towards each other to press the two web portions together, and means for displacing the pressing means while pressing the web portions together so as to follow the travelling webs. Thereby, the pressure may be exerted by the pressing means for a sufficiently long time while the webs continue to travel. The pressing means may comprise jaws.

The web portions may be made of a material, or may be coated or impregnated with a material, which is adhesive at normal room temperature, the web portions being connected by the pressure exerted by the jaws.

However, means may be provided for heating one of the jaws or both jaws preferably before the jaws exert pressure on the web portions whereby to connect the web portions under heat and pressure. In this case, the web portions may be made of a material, or may be coated or impregnated with a material, which becomes adhesive under heat.

Means may be provided for actuating the heating means when the end of a web approaches the jaws.

If the end portion of a web is to be coated or impregnated with an adhesive material, a storage container for the adhesive material may be provided, means being provided for applying the adhesive material to the web portion before the web portion reaches the jaws. Preferably, both web portions to be connected are coated or impregnated by the applying means.

2

Means may be provided for cutting off unessential parts of the web portions to be connected together.

BRIEF DESCRIPTION OF THE DRAWINGS

Other objects and advantages of the invention will become clear from the following detailed description thereof when read in conjunction with the accompanying drawings, which are given by way of example and in which:

10 FIG. 1 shows a side view, in section, of a first embodiment of the invention;

FIG. 2 shows a side similar to FIG. 1 but with some of the parts displaced from the positions in which they are shown in FIG. 1;

15 FIG. 3 shows a view taken in section along the line III—III of FIG. 1 omitting some of the parts shown in FIG. 1;

FIG. 4 shows a side view, in section, of a second embodiment of the invention;

20 FIG. 5 shows a view taken in section along the line V—V of FIG. 4;

FIG. 6 shows in side view, a modified detail of the embodiment of FIGS. 4 and 5;

FIG. 7 shows a side view, in section, of a third embodiment of the invention; and

25 FIG. 8 shows a view taken in the direction of the arrow A of FIG. 7, some of the parts of FIG. 7 being omitted.

DESCRIPTION OF EMBODIMENTS

30 The embodiment of FIGS. 1 and 2 comprise two reels 1a and 1b for supply webs 2a and 2b, of which the web 2a is travelling, for example, to a packing machine, and the web 2b is a stand-by web. The webs 2a and 2b are 35 guided by guide rollers 3a and 3b respectively to guides 4a and 4b which are rotatably mounted by pivots 5a and 5b. In their normal, operative, position, the guides 4a and 4b are inclined relatively to each other as shown in FIG. 1. On the guides 4a and 4b, the guide rollers 40 3a and 3b are rotatably mounted. The guides 4a and 4b also carry cutters 8a and 8b for cutting the webs. The guides 4a and 4b together with the guide rollers 3a and 3b and the cutters 8a and 8b are turnable independently of each other about the pivots 5a and 5b respectively into 45 retracted positions so as to facilitate introducing the respective web 2a or 2b. Web retainers 9a and 9b are pivotally secured to the guides 4a and 4b for retaining the webs 2a and 2b. The guides 4a and 4b are each provided with perforations 10a and 10b connected by ducts 50 11a and 11b in the guides 4a and 4b, and by pipes 12a and 12b to a source of suction (not shown) to enable the webs 2a and 2b, when not travelling, to be held by suction against the guides 4a and 4b.

When the end of one of the webs, for example the 55 web 2b, is to be inserted into the device the guide 4b is moved manually into the retracted position as shown in FIG. 2 with respect to the guide 4b, the end of the web 2b is then manually passed over the guide roller 3b, threaded between the web retainer 9b and the guide 4b and laid on the guide 4b over the perforations 10b so as to be retained against the guide 4b by suction. The guide 4b is then pivoted back into the position shown in FIG. 1.

The cutters 8a and 8b are slidable in slots 17a and 65 17b in the guides 4a and 4b and are pivotally connected to arms 18a and 18b of two pairs of three-armed levers indicated generally by reference numerals 19a and 19b (only one of each pair being visible in FIG. 1). The levers 19a and 19b are pivotally mounted by pivot pins 70 20a and 20b on projections 21a and 21b on the guides 4a and 4b and have further arms 22a, 22b and 23a, 23b respectively. Tension springs 25a and 25b urge the cutters

8a and **8b** towards the webs **2a** and **2b** and towards a stationary counter-element **63**, and tend to pivot the levers **19a** and **19b** about the pivot pins **20a** and **20b**, the cutters **8a** and **8b** and the levers **19a** and **19b** being retained in the positions shown in FIG. 1 by engagement of the lever arms **23a** and **23b** with a common pawl **27**. As shown in FIG. 3, the pawl **27** is pivotally mounted on the main frame of the arrangement, an electromagnet **61** being provided for pivoting the pawl **27** against the action of a spring **62**. Two pairs of stops **28a** and **28b** (only one of each pair being visible in FIG. 1) pivotally mounted on the projections **21a** and **21b** by shafts **29a** and **29b** are manually turnable into locking positions to engage the arms **23a** and **23b** and thereby to retain the levers **19a** and **19b** and therewith the cutters **8a** and **8b** against the action of the springs **25a** and **25b** when the pawl **27** is released on energization of the electromagnet **61**. One of the stops **28a** is shown in its locking position in FIG. 1. Curved stationary abutments **30a** and **30b** are arranged for co-operating with arms **31a** and **31b** of the stops **28a** and **28b** to ensure that the stops **28a** and **28b** are pivoted into their locking positions as shown with respect to stop **28b** in FIG. 2, when the respective guides **4a** and **4b** are pivoted into their retracted positions. The pawl **27** is magnetically releasable so that after release of the pawl **27** that cutter **8a** or **8b** is operable which is not secured in position by the stops **28a** or the stops **28b**.

Two heating jaws **32a** and **32b** are provided which are normally spaced apart from each other. The jaws **32a** and **32b** are each mounted on a parallelogram guide arrangement comprising links **33a** and **33b** carried on links **34a**, **34b**, **35a** and **35b**, which are pivotally connected to a frame comprising end members **37a** and **37b** connected by transverse members **38**, **39** and **40** (FIG. 3). The arms **34a** and **34b** are linked by meshing toothed ends of arms **41a** and **41b** which ensure corresponding movements of the arms **34a**, **35a** and **34b**, **35b**. The jaws **32a** and **32b** are urged together by a tension spring **42** but are normally held apart by a connecting member **44** pivoted to a lever arm **45** which is rigid with a lever arm **46** retained by a pawl **47**. The jaws **32a** and **32b** are provided with electric heating elements **48a** and **48b** (not shown which, when the jaws **32a** and **32b** are in the positions shown in FIG. 1, are connected to contacts comprising contact elements **49a** and **49b** bearing against resilient contact arms **50a** and **50b**). Each of the reels **1a** and **1b** lasts for a considerable time, for example two hours. In order to ensure that the heating elements **48a** and **48b** are supplied with electric current only shortly, for example about 5 minutes, before a reel is exhausted, known devices are provided for controlling the supply of electric current to the contact arms **50a** and **50b** from a current supply source (not shown). One of these devices, associated with the reel **1a**, is shown, and comprises contact elements **59** controlled by a feeder arm **60** resiliently urged against the peripheries of the reel **1a**, the contact element **59** being electrically connected in series with the contact arm **50a** and **50b**. A similar control device which in part is shown in broken lines in FIG. 1 co-operates with the reel **1b**.

The frame comprising the end members **37a** and **37b** and the transverse members **38**, **39** and **40** (see also FIG. 3) is carried on an arm **52** which is pivotable about a shaft **53** mounted in uprights **541** and **551** forming parts of a main frame of the arrangement. The arm **52** is retained in the position shown in FIG. 1 by engagement of the link **33a** with an abutment **54** fixed to the main frame.

The retaining pawl **47** forms one arm of a two-armed lever pivotally mounted on the arm **52** and releasable by energization of an electromagnet **55** linked to the pawl **47** by a two-armed lever **56** turnable about a fixed pivot pin **57**. On release of the pawl **47**, the jaws **32a** and **32b** snap towards each other under the action of the

tension spring **42**, the link **33a** disengaging the abutment **54**, whereupon the arm **52** pivots downwards about the shaft **53**. An abutment lever **65** is linked to the arm **52** through the lever arm **46** and arranged for co-operation with a stationary abutment **66**.

In operation, one of the webs **2a** and **2b** travels between the spaced-apart jaws **32a** and **32b**, the beginning of the other stand-by web lying stationary between the jaws. As shown in FIG. 1, the web **2a** is the travelling web and the web **2b** is the stand-by web. After the stand-by web **2b** has been placed in position on the guide **4b** by an operator, the operator manually turns the stop **28a** by means of its arm **31a** from its locking position shown in FIG. 1 into its non-locking position. By turning the guide **4b** while placing the stand-by web **2b** into position, the stop **28b** is automatically turned from its non-locking position shown in FIG. 1 into its locking position. When by means of the respective feeler arm **60** the approach of the end of the travelling web **2a** has been sensed the contact elements **59** controlling the supply of electric current to the heating elements **48a** and **48b** are closed whereby the jaws **32a** and **32b** are heated. Subsequently, when the feeler arm **60** senses the end of the travelling web, the electromagnets **61** and **55** are energized and attract. Thereby, the pawl **27** releases the cutter levers **19a** and **19b** with the cutters **8a** and **8b**. By energization of the electromagnet **55**, the pawl **47** is released and the heated jaws **32a** and **32b** are forced together under the action of the spring **42** and press together and heat the adjacent web portions under pressure whereby they are welded together. While the jaws **32a** and **32b** move with the webs, the arm **52**, which carries the jaws **32a** and **32b**, turns about the shaft **53** under the action of gravity. Furthermore, when the pawl **27** is released the end of travelling web **2a** is cut off by the cutter **8a** in co-operation with its stationary counter-element **63**. In the foregoing it has been assumed that the webs are made of a material which becomes tacky under heat. Alternatively, the webs may be coated or impregnated with a material that becomes tacky under heat.

When the jaws have nearly reached the end of their travel, as shown in FIG. 2, they are opened when the abutment lever **65** rigid with the lever arm **46** strikes the stationary abutment **66** causing the pawl **47** to re-engage the lever arm **46**. Subsequently, the arm **52** with the jaws **32a** and **32b** is manually returned into its position shown in FIG. 1 and locked by engagement of the link **33a** with the abutment **54**. The cut-off remainder of the web **2a** is removed by hand. A fresh web from a fresh reel is now introduced between the guides **4a** and **4b** and the stops **28a** and **28b** are adjusted, the introduction of the fresh web being facilitated by first turning the guide **4a** with the cutter **8a** into the retracted inoperative position as described above with respect to the guide **4b** whereby access to the guide **4a** is facilitated.

It should be noted that FIG. 2 illustrates the web **2a** at the beginning of its travel and the guide **4b** turned for inserting the stand-by web **2b**. FIG. 1 illustrates the further travel of the web **2a** but shows the stop **28b** prior to the guide **4b** being turned. Furthermore, the electric circuits for the electromagnets have not been shown since their arrangements are obvious.

In the embodiment of FIGS. 4 and 5, two webs **102a** and **102b** are guided by guide rollers **103a**, **103b**, **104a**, **104b** between a pair of heating jaws **105a** and **105b**, which are resiliently mounted on rotatable supports **106a** and **106b** carried on shafts **107a** and **107b**. The jaws **105a** and **105b** are heated electrically through sprung contacts **110** provided on side walls **109**, (FIG. 5). The jaws **105a** and **105b** are provided with heater elements **111a** and **111b** of low ohmic resistance, electric current being supplied at low voltage to avoid or reduce arcing. In FIG. 4, the web **102a** is shown travelling between the jaws **105a** while the web **102b** is the stand-by web. When

a feeler arm (not shown) detects in a manner analogous to that described with reference to the first embodiment that the web 102a is almost exhausted, the heating elements receive current and heat the jaws 105a and 105b. When the end of the web 102a approaches the jaws 105a and 105b, a single revolution clutch indicated generally by reference numeral 112 (FIG. 5) is operated to rotate the shafts 107a and 107b and thereby to rotate the jaws 105a and 105b through one revolution. The webs extend between rollers 114a and 114b to the jaws 105a and 105b and as the end of the web 102a approaches the roller 114b is rotated to feed the web 102b towards the jaws 105a and 105b, which approach each other and press the webs 102a and 102b together so that the webs 102a and 102b are welded together, the jaws 105a and 105b travelling with the webs 102a and 102b and being pressed inwardly of the supports 106a and 106b. Subsequently, the jaws 105a and 105b move away from each other and after completion of one rotation come to rest.

Cutters 115a and 115b are provided for cutting the webs 102a and 102b, and are controlled by electromagnets 116a and 116b. Two-armed levers 118a and 118b operated by the electromagnets 116a and 116b are formed with pawls 119a and 119b engageable with levers 120a and 120b which are rigidly connected with further levers 121a and 121b, which in turn are pivotally connected to the cutters 115a and 115b. Tension springs 122a and 122b tend to urge the cutters 115a and 115b towards a counter-element in the form of a fixed bar 114 extending between the paths of the webs 102a and 102b so that when the electromagnet 116a, for example, is energized the pawl 119a releases the lever 120a and the tension spring 122a moves the cutter 115a against the web 102a, which is cut between the cutter 115a and the bar 114.

For facilitating the introduction of the webs 102a and 102b, an idling roller 125 is provided between the rollers 114a and 114b, which have raised peripheral portions 126a and 126b extending around half of their peripheries. When the rollers 114a and 114b are in the position in which they are shown in FIG. 4, a gap is provided between each of the rollers 114a, 114b and the idling roller 125. Abutments 129a and 129b are provided below these gaps. On insertion of the stand-by web, which in the case illustrated in FIG. 4 is the web 102b, the web 102b is threaded manually between an abutment 129b. The abutments 129a and 129b are pivotable about shafts 130a and 130b under the control of cam follower levers 131a and 131b co-operating with cams 132a and 132b provided on the shafts which carry the rollers 114a and 114b. When the roller 114b is rotated so that the raised portion 126b contacts the web 102b for feeding the web 102b towards the jaws 105a and 105b the abutment 129b is pivoted in a clockwise direction, as viewed in FIG. 4, and out of the path of the web 102b, which by means of the idling roller 125 and the raised portion 126b of the roller 114b is fed between the spaced-apart jaws 105a and 105b.

The webs 102a and 102b may be made of a material, or coated or impregnated with a material that becomes tacky under heat.

Alternatively, only the ends of the webs 102a and 102b may be made of or coated or impregnated with such material. Still alternatively, the web ends may be adhesive when cold or may be coated or impregnated with an adhesive. If the adhesive or the adhesive end of the web is tacky while cold, it is not necessary to heat the jaws 105a and 105b. For coating a portion of the newly introduced web, which in the present case is the web 102b, with an adhesive, a container 136 for an adhesive (see FIG. 5) is provided having electric means 137 for heating the adhesive in the container 136. A roller 138 has an interior space 139 communicating with the interior of the container 136, a further heating element 140 being provided in the space 139 for heating

the adhesive which flows from the container 136 into the space 139. The space 139 communicates with the outside of a segment 142 on the roller 138 through a plurality of ducts 143. A single revolution clutch 141 is provided for rotating the roller 138 through a single revolution alternatively in a clockwise sense, or in the opposite sense, as viewed in FIG. 4. In the present case, the web 102a is the travelling web and the roller 138 is therefore rotated in an anticlockwise direction as viewed in FIG. 4 to provide a coat of adhesive near the end of the web 102a through the ducts 143. The end of the web 102b is then fed as described hereinbefore and is pressed by the jaws 105a and 105b against the coated portion of the web 102a.

When the roller 138 is in its position shown in FIGS. 4 and 5, the ducts 143 are directed upwards to avoid leakage of the adhesive. The outermost ends of the ducts 143 are widened to form small cups in which the adhesive accumulates. The single revolution clutch 141 is connected by drive chains 144 and 145 and guide sprockets 146, 147, 148 and 149 to the roller 138 for the adhesive while the single revolution clutch 112 is connected by gears 150, 151, and 152 to the shafts 107a and 107b for rotating the jaws 105a and 105b. The clutches 112 and 141 are of similar construction and the same reference numerals have been used to indicate the components of these clutches, which will now be described in detail.

Each of the clutches 112 and 141 comprises a disc 115 keyed to a shaft 156 and a coupling arm 157 pivotally mounted on the disc 115 and carrying a roller 158. The coupling arm 157 is formed with a projection 160 which is engageable in a recess 161 in a hub 162 solid with the gear wheel 150 for coupling the shaft 156 to the gear wheel 150. A release member 164 which is pivotally mounted on wall 109 is urged by a spring 165 into a position of abutment against a fixed abutment 167, in which it is held by a pawl 168. An electromagnet 169 is provided for releasing the pawl 168. As the disc 115 rotates the roller 158 strikes the release member 164. The coupling arm 157 is therefore pivoted relative to the disc 115 against the action of spring 171 to remove the projection 160 from the recess 161. When the electromagnet 169 is energized and releases the pawl 168 from the release member 164 the roller 158 is able to pivot the release member 164 against the action of spring 165 and the projection 160 is therefore able to engage in the recess 161 to provide a drive connection.

Beyond the jaws 105a and 105b, the web 102a is guided by guide rollers 173.

FIG. 6 illustrates a modified jaw 205 which may replace the jaws 105a, 105b of the embodiment of FIGS. 4 and 5. The jaw 205 of FIG. 6 is pivotally mounted on a support 206, a tension spring 207 being connected between the jaw 205 and a member 208 carrying the support 206.

A heating element 208 in the form of a flat plate is provided on the jaw 205 and can be supplied with electric current through a contact element 209 when the jaw 205 is in its rest position shown in full lines in FIG. 6. When the jaw 205 rotates from this rest position for clamping the webs together in co-operation with a similar jaw on the opposite side of the webs, the heating element 208 disengages from the stationary contact element 209 and travels substantially parallel to itself, as shown in broken lines, owing to the action of the other jaw, the jaw 205 pivoting relative to the support 206 and thereby tensioning the spring 207, until the jaw 205 and the corresponding jaw on the opposite side of the webs move away from one another sufficiently to enable the tension spring 207 to pivot the jaw 205 back to its initial position relative to the support 206.

The third embodiment of FIGS. 7 and 8 comprises reels 301a and 301b for supplying webs 302a and 302b past rollers 303a and 303b and through web guides 304a and

304b and cutters **308a** and **308b** to jaws **310a** and **310b**. Drive chains **311a** and **311b** carry the jaws **310a** and **310b** and extend around sprockets **313a**, **313b**, **314a**, **314b** which are carried on shafts **316a** **316b**, **317a**, and **317b** journaled in side walls **318** and **319** (see also FIG. 8). An electric motor **321** is connected to a main drive shaft **322** carrying a single revolution clutch **324** which controls the transmission of drive through a gear wheel **325** on the shaft **322** to gear wheels **326** and **327** provided on the shafts **316a** and **316b** for driving the sprockets **313a** and **313b**. The construction of the clutch **324** is similar to that of the clutches **112** and **141** and will therefore not be described in detail.

When the jaws **310a** and **310b** are in their positions shown in FIGS. 7 and 8, they are engaged at one end by resiliently mounted contact elements **330a** and **330b**, their other ends being electrically connected by an electrical conductor **331** which is insulated from other parts of the embodiment. The contact elements **330a**, **330b** and the electrical conductor **331** serve to supply electric current to heating elements **333a** and **333b** on the jaws **310a** and **310b**.

The cutters **308a** and **308b** are carried on arms **335a** and **335b**, which are connected together by a link **336**, and are turnable about pivots **337a** and **337b**. The arms **335a** and **335b** are rigid with arms **339a** and **339b** which are urged towards one another by tension springs **340a** and **340b**. The arm **339b** is pivoted to the armature of an electromagnet **342** which is operable to pivot the arm **339b** in either direction about the pivot **337b** from the position in which the arm **339b** is shown in FIG. 7. When the arm **339b** is pivoted clockwise about the pivot **337b** from its position shown in FIG. 7, the cutter **308B** cuts the web **302a**, whereas when the arm **339b** is pivoted in the opposite direction, the cutter **308a** cuts the web **302a**.

The shaft **317a** is carried by a pair of plates **345** which are turnable about the axis of the shaft **316a**.

Guide surfaces **346a** and **346b** on guide members **347a** and **347b** extend parallel to the paths of the webs for guiding the jaws **310a** and **310b** and thereby preventing turning of the plate **345** until the jaw **310a** has reached the end of the guide surface **346a** nearest the sprocket wheel **314a**.

An electromagnet **349** controls a pawl **350** for operating the single revolution clutch **324**.

Sprockets **353** and **354** and a drive chain **355** connect the main drive shaft **322** to a feed roller **357** (FIG. 8) which co-operates with a resiliently mounted guide roller **358** for feeding the web **302b** from a guide roller **359**.

The rollers **303a** and **303b** are formed with recesses **360a** and **360b** extending partly around their peripheries and are disposed on opposite sides of a pair of rollers **361a** and **361b**. While the travelling web, which in the present case is the web **301b**, is being fed through the device, the end of the stand-by web, which in the present case is the web **302a**, is inserted into the recess **360a** between the roller **303a** and the roller **361a**. The roller **303a** is then rotated for example manually by an operator, through one revolution, a click-stop device being provided for arresting the roller **303a** after one revolution, so that a predetermined length of the web **302a** is fed past the guide **304a**. When the approach of the end of the web **302b** on the reel **301b** is sensed by known means (such as the feeler arms **60** of FIG. 1) electric current is passed through the heating elements **333a** and **333b** by means of the contacts **330a** and **330b** approximately five minutes before the reel **301b** is exhausted. Thereby the jaws **310a** and **310b** are heated. The electromagnets **342** and **349** are energized. Energization of the electromagnet **342** causes the cutter **308b** to cut the web **302b**. The electromagnet **349** operates the single revolution clutch **324** to provide drive to the sprocket wheels **313a** and **313b** for three rotations of the main drive shaft **322**. The jaws **310a** and **310b** move towards one another, press together the lead-

ing end of the web **302a** and the rear end of the web **302b**, and travel along the guide surfaces **346a** and **346b** together with both web ends while welding the ends of the webs **302a** and **302b** together. When the jaw **310a** slides from the right hand end, as viewed in FIG. 7 of the guide surfaces **346a**, the plates **345** are free to pivot by a small amount about the shaft **316a** as the jaws **310a** and **310b** travel around the sprocket wheels **313a** and **313b** whereby to avoid jamming. When the main drive shaft **322** has completed three rotations, the jaws **310a** and **310b** are again in their positions shown in FIGS. 7 and 8, and the drive to the sprocket wheels **313a** and **313b** terminates. The web **302a** is now the travelling web and a new web, replacing the web **302b** is threaded between the rollers **303b** and **361b** as the new stand-by web. Adjustment screws **363**, of which only one is shown, limit the amount of pivoting of the plates **345**.

Each of the above-described splicing devices may be employed to splice together webs of material such as thin sheet cellulose or other synthetic material which can be welded together under heat and pressure whereby the use of adhesive strips for joining together the ends of the webs may be avoided. The jaws travel with and in contact with the webs to ensure that the webs are securely welded together. Alternatively, a suitable glue may be provided to the web portions to be welded together. Again, if the web portions are tacky while cold the heating of the jaws may be omitted. When employing heated jaws the heat is stored in the jaws. Therefore it is not necessary to supply electric current to the jaws by means, for example, of sliding contacts or flexible cables while the jaws are moving.

It should be clearly understood that the embodiments hereinbefore described in detail are given by way of example only. Many modifications, additions and omissions are possible without departing from the spirit of this invention.

What is claimed is:

1. A splicing device comprising pressing means, means for feeding a travelling web and the leading portion of a stand-by web between said pressing means, means for moving said pressing means towards each other to press said leading portion and a portion of said travelling web together, and displacing means comprising a swingable arm carrying said pressing means, said arm being arranged for displacing said pressing means along the path of travel of said web portions to cause said pressing means when pressing said web portions together to travel jointly with said web portions along the path of travel of said travelling web, whereby the entire length of said web portions are in contact with said pressing means during the travel of said pressing means along said path.

2. A splicing device comprising pressing means, means for feeding a travelling web and the leading portion of a stand-by web between said pressing means, means for moving said pressing means towards each other to press said leading portion and the portion of said travelling web together, and displacing means for causing said pressing means while pressing said web portions together, to travel jointly with said web portions along the path of travel of said travelling web, said displacing means comprising endless belts carrying said pressing means, whereby the entire length of said web portions are in contact with the pressing means during the travel of said pressing means along said path.

3. A splicing device comprising pressing means, means for feeding a travelling web and the leading portion of a stand-by web between said pressing means, pre-heating means for heating the pressing means, means for rendering the pre-heating means operative at a predetermined interval before the arrival of the trailing end of the travelling web, means for moving said pressing means towards each other to press a portion of said travelling web and said leading portion of the stand-by web together and causing said pre-heating means to be rendered inoperative, and displacing

means for causing said pressing means while pressing said web portions together to travel jointly with said web portions along the path of travel of said travelling web, said displacing means comprising rotatable rollers carrying said pressing means, said pressing means being arranged movably relatively to the peripheries of said rollers to displace effective parts of said pressing means, while pressing said web portion together, in a substantially rectilinear path, whereby said web portions are spliced by welding effected by the heat stored in said travelling pressing means.

4. A splicing device as defined in claim 3, and further comprising means connecting said pressing means slidably to said rollers, and spring means urging said pressing means outwards from the peripheries of said rollers.

5. A splicing device as defined in claim 3, and further

comprising means for pivotally connecting said pressing means to said rollers.

6. A splicing device as defined in claim 3, and further comprising means for applying a thermally adhesive material to at least one of said web portions before the same are pressed together by said pressing means.
